UNITED STATES PATENT OFFICE.

PAUL T. HERTZOG, OF NEWARK, NEW JERSEY, ASSIGNOR TO HENRY S. STRAUSS AND SOLOMON HEILNER, BOTH OF NEW YORK, N. Y., AND SAMUEL STRAUSS, OF NORTH BROOKFIELD, MASSACHUSETTS.

DESIGN FOR A CORSET.

SPECIFICATION forming part of Design No. 12,773, dated February 21, 1882.

Application filed January 9, 1882. Term of patent 14 years.

To all whom it may concern:

Be it known that I, PAUL T. HERTZOG, of Newark, in the county of Essex and State of New Jersey, have invented and produced a new and original Design for Corsets, consisting of a new, useful, and original pattern or configuration to be placed on or worked into corsets; and I do hereby declare that the following is a full, clear, and exact description of the same.

My invention is in the nature of a new and original pattern or configuration for the lower part of corsets.

This design consists in making the lower section of the corset, between the front and the back steels, of a pattern or configuration resembling an arc or crescent having a series of corrugations or ridges from the front to the back, and parallel to the lower edge of the corset.

The accompanying photographs show a corset containing my design.

Figure 1 is a frontal side view, and Fig. 2 a back view, of a corset. The lower part shows my invention, and is of the pattern or configuration indicated.

A series of parallel ridges or corrugations start near the front steels, pass across the abdominal parts, the hips, and loins on each side, and terminate near the back steels.

When the corset is expanded to the shape it assumes when it is worn the lower part on each side is in the shape or of the pattern of an arc springing from the front and back steels, curving across and having its highest point over the hip.

The upper part of the corset may be made of any design preferred.

The design of the corset shown in the photographs consists of a series of vertical corrugations extending throughout the entire upper structure of the corset, with short cross-pieces over the upper part of the bosom; but these may all be varied, and any suitable design may be worked out in the upper part of the corset, the design or configuration of which is entirely immaterial, so far as it relates to the design or pattern herein described and claimed as my invention, which is intended to be and may be placed on or worked into corsets of any kind.

Having thus described my invention, what I claim as new, and desire to secure by Letters Patent, is—

1. The strip or section herein described, being of the pattern or configuration of an arc or crescent with longitudinal ridges or corrugations to be placed on or worked into corsets, substantially as described and shown.

2. The new design for a corset described, consisting of any suitable upper structure or design for a corset, in combination with a lower part or section having the pattern or configuration of an arc or crescent extending from the front to the back steels, and provided with ridges or corrugations parallel to the lower edge of the corset throughout its entire length, substantially as shown and described.

PAUL T. HERTZOG.
